UNITED STATES PATENT OFFICE.

FREDERICK H. JONES, OF WAKEFIELD, MASSACHUSETTS, ASSIGNOR TO
TYER RUBBER CO., OF ANDOVER, MASSACHUSETTS.

HOT-WATER BOTTLE.

SPECIFICATION forming part of Letters Patent No. 738,544, dated September 8, 1903.

Application filed October 22, 1902. Serial No. 128,228. (No model.)

To all whom it may concern:

Be it known that I, FREDERICK H. JONES, of Wakefield, county of Middlesex, State of Massachusetts, have invented an Improvement in 5 Hot-Water Bottles, of which the following description, in connection with the accompanying drawings, is a specification, like characters on the drawings representing like parts.

This invention relates to hot-water bottles, 10 and has for its object to provide the stopper thereof with improved means for retaining it in connection with the bottle, so that it will not be lost.

My invention consists in a hot-water bottle 15 having a stopper provided at its lower end with a headed stud, a retaining device for said stopper, consisting of a chain which extends into the bottle, a clip connected to one end of said chain, comprising a plurality of 20 arms having inturned ends which engage said headed stud, and a compressible retainer connected to the opposite end of said chain.

Figure 1 shows in vertical section the upper end portion of a hot-water bottle and stopper, 25 and in elevation a retaining device for said stopper embodying this invention. Fig. 2 is a detail of the stopper, showing particularly the means for attaching the chain thereto. Fig. 3 is a detail of the means for attaching 30 the chain to the stopper, and Fig. 4 is a detail showing the blank from which is formed the means for attaching the chain to the stopper.

a represents the hot-water bottle, which is of any usual or suitable construction, *b* being 35 the neck thereof and *c* the stopper. At the lower end of the stopper *c* a headed stud *c'* is employed for the purpose of securely hold-

ing the washer *c*², and to said headed stud my improved retaining device is attached.

The retaining device consists, essentially, of 40 a chain *d* of any suitable length, having at its lower end a compressible retainer which, as herein shown, consists of a two-armed spring-acting yoke *d'* of suitable size to pass through the opening at the neck of the bottle when 45 properly compressed, but which may be withdrawn with considerable difficulty. The chain is attached to the lower end of the stopper by a clip, which consists of a plate having a plurality of arms *e*, which are upturned and 50 inturned to form hooks, which engage the head of the stud *c'*, and said plate has two apertures through it to form an eye, through which the endmost link of the chain passes.

Having thus described my invention, what I 55 claim as new, and desire to secure by Letters Patent, is—

A hot-water bottle having a stopper provided at its lower end with a headed stud, a retaining device for said stopper consisting 60 of a chain which extends into the bottle, a clip connected to one end of said chain comprising a plurality of arms having inturned ends which engage said headed stud and a compressible retainer connected to the opposite 65 site end of said chain, substantially as described.

In testimony whereof I have signed my name to this specification in the presence of two subscribing witnesses.

FREDERICK H. JONES.
